UNITED STATES PATENT OFFICE.

GEORGE S. PEARSON, OF WATERBURY, ASSIGNOR TO THE TUCKER MANUFACTURING COMPANY, OF WATERVILLE, CONNECTICUT.

DESIGN FOR A DRAWER-PULL HANDLE.

SPECIFICATION forming part of Design No. 20,246, dated October 28, 1890.

Application filed September 19, 1890. Serial No. 365,471. Term of patent 7 years.

To all whom it may concern:

Be it known that I, GEORGE S. PEARSON, a citizen of the United States, residing at Waterbury, in the county of New Haven and State 5 of Connecticut, have invented and produced a new and original Design for Drawer-Pull Handles; and I do declare the following to be a full, clear, and exact description of the same, reference being had to the accompanying drawings, forming a part thereof.

Figure 1 is a representation of my novel drawer-pull handle attached to a base-plate as in use; Fig. 2, a view of the handle detached, and Fig. 3 is a section on the line $x x$ 15 in Fig. 1.

The leading feature of my design consists of a handle the edges and sides of which have a scalloped or corrugated outline.

What I claim is—

The design for a drawer-pull handle herein shown and described, the same consisting of a handle the edges and sides of which have a scalloped or corrugated outline.

In testimony whereof I affix my signature in presence of two witnesses.

GEORGE S. PEARSON.

Witnesses:

A. M. WOOSTER,
ARLEY I. MUNSON.
